UNITED STATES PATENT OFFICE

BUREN MOAD, OF TOLEDO, OHIO

CANDY COTTON FORMING MACHINE

Application filed September 10, 1929. Serial No. 391,637.

My invention has for its object to provide an efficient means for producing candy cotton and which is so constructed that carbonization of the sugar used in the formation of the candy will be entirely eliminated and the revolving cotton forming member may be rotated at an exceedingly high speed without danger of fracture of the member. The invention also provides a means for 10 making electrical connection with the heater located in the rotatable member and for regulating the supply of current through the electric motor that rotates the rotatable member and the heater located in the rotatable member.

The invention may be contained in structures that vary in their details and, to illustrate a practical application of the invention, I have selected a structure containing the 20 invention as an example of the various forms of structures that embody the invention, and shall describe the structure selected hereinafter. The structure selected is shown in the accompanying drawings.

25 Fig. 1 illustrates a perspective view of the candy cotton forming machine. Fig. 2 is a view of a vertical section through a part of the machine shown in Fig. 1. Fig. 3 is a view of a section of one side of the part of 30 the sugar spinning member. Fig. 4 is a diagram of the electric connections of the motor that operates the spinner and of the heater located within the spinner. Fig. 5 illustrates a view of a section of a part of the machine 35 and shows a top view of the brushes that make connection between the heat coil of the spinner and the external circuit. Fig. 6 is a top view of a part of the heat coil and illustrates the means for connecting the end of 40 the heat coil to prevent short circuiting and at the same time to prevent carbonization at the ends of the heat coil. Fig. 7 illustrates a cross section of the heat coil when flattened to form. Fig. 8 illustrates a view of the 45 heat coil wound preparatory to flattening. Fig. 9 illustrates a side view of the heat coil showing the latticed apertures.

The candy cotton machine has a pedestal 1 that is provided with a relatively large base 2 in which is located the electric motor

3 that is connected to the porcelainized sheet metal spinner 4 by means of a spindle 5 and a plate 6. A bowl 7 is supported on the top of the pedestal 1 so as to surround and contain the spinner 4 and provide for the collection of the candy cotton that is produced by rotating the spinner 4 at a high rate of rotation. The base 2, being large, affords a means for preventing creeping of the machine with reference to a supporting table on 55 which it may be placed.

The bowl 7 may be secured intermediate a flange 10 and a sleeve 11 which is threaded onto the upper end of the pedestal 1. Within 60 in the sleeve 11 is located the electrical contacts that complete the connection between the rotating spinner 4 and the external circuit. A plate 12 is connected to the upper end of the pedestal 1. A pin 13 is secured to the plate 12 and a pair of arms 14 are 65 pivotally supported on the pin 13. The arms 14 are provided with arcuate contacts 15 that fit opposite sides of the surface of the ring 16 that is insulatingly supported on the upper end of the spindle 5. The contacts 15 may be formed of carbonaceous material of the type commonly used, and are located on opposite sides to prevent arcing by reason of any vibration that may be set up in the spindle 5 which rotates at a very 70 high speed. Any lateral movement of the ring 16 will cause increased contact pressure with one or the other of the arcuate contacts 15 and thus there will be maintained a substantially uniform contact pressure between 75 the contacts 15 and the ring 16, notwithstanding any vibration of the spindle 5. The contact pressure will be maintained by means of the tension spring 17 that interconnects the ends of the arms 14 on the side 80 of the ring 16 opposite to that on which the pin 13 is located.

The ring 16 is connected to one of the ends of the heat coil 20 located within the spinner 4. The other end of the heat coil 20 is 85 connected to the ring 21. Arcuate contacts 22 are located in contact with the ring 21 and on opposite sides thereof and are supported in the arms 23. The arms 23 are 90 pivotally supported by a pin located on the 95 100

plate 24 which is supported in the sleeve 11. The contacts 22 are supported in the arms 23 and are interconnected by a spring in the same manner that the contacts 15 are supported in the arms 14, and the arms are interconnected by a spring in the same manner that the arms 14 are interconnected by the spring 17. The arms 23 are supported by a pin on the plate 24 in the same manner that the arms 14 are supported by the pin 13 on the plate 12.

The heat coil 20 is formed of a flexible band spirulate in form and flattened to produce, in cross section, an arc substantially 15 in length the same as the length of the radian of the arc which produces a latticed appearance as shown in Fig. 9. The edges of contiguous turns being located in close proximity to each other and the opposite 20 sides of the turns crossing each other to form minute openings through the lattice construction thus produced, the openings, however, being in surfaces that curve and the center of each arcuate section, taken on 25 a plane in which the axis of the machine is located being located in the plane at right angles to the chord connecting the ends of the arc of the section as shown in Figs. 7 and 8.

30 The heater is located within the spinner member 4. The spinner member 4 is a channelled member that is formed from sheet metal by die pressing it to shape to form a continuous annular non-joined member having a central web 30 and the flanges 31. The depth of the channel thus formed being substantially the same, or preferably greater than the width of the bottom of the channel formed by the web 30. The flanges 31 are 35 located in parallel planes and the bottom 30 is circular in form. The channel is so formed that its cross section in a plane through the center of the member is such that the bottom of the channel is arcuate, 40 the arc having a length substantially that of the length of the radian of the arc, and joined by curved portions 32 with the flanges 31. The width of the interior of the bottom 30 is substantially the same as the width 45 of the heater 20 and a curvature of the web of the channel member is substantially the same as the curvature of the cross section of the heater 20. The bottom of the spinner member 4 is provided with a plurality 50 of slots 33 that extend diagonally with respect to the parallel flanges and so as to form spaces through which the candy cotton may pass and also form supporting parts for the flexible band of which the 55 heater is formed to maintain the heater in position against the centrifugal force that is exerted by the high rate of rotation to which the heater and spinner are subjected. Preferably, the slots extend to the rounded 60 surfaces 32 of the corners of the spinner to

prevent retention of any of the molten sugar.

The spinner 4 is connected to the spindle 5 by means of the plate 6 which is secured by means of a threaded washer 35. The plate 6 has a raised central portion 36 which fits the inner edge of the lower flange 31 of the spinner member 4. A cover plate 37 is located on the top of the spinner. It has a depressed channel portion 38 that fits within and depends below the inner edge of the upper flange 31 of the spinner 4. The cover plate 37 is provided with a central opening 39 through which sugar may be inserted into the interior of the parts formed by the plates 6 and 37 and the spinner member 4. When the spindle 5 is rotated at a high speed, and the heater 20 is rendered hot by an electric current, the sugar is melted and as it is melted it escapes through the openings formed by the latticing of the opposite sides of the curved spirulate band that forms the heat coil and, by reason of the centrifugal force and the shape of the heat band and supporting web of the spinner member, the candy cotton will be formed through the slots of the spinner member and carbonization of the sugar will be prevented because of the curvature of the section of the bottom of the spinner member and of the heat coil, since all of the hotter and, consequently the less viscous, sugar will, by the centrifugal force, work out through the central parts of the heat coil in advance of carbonization. The curved corners 32 of the spinner member and the curved edges of the flattened spirulated heat coils prevents the collection of melted sugar at these points, and, consequently, prevents the carbonization of the sugar at these points or any part of the spinner member.

The ends of the heat coil are connected through the wires 45 that extend through a wooden block 46 which overlaps the ends of the heat coil 20. Preferably, the block 46 has a tongue 47 that is located between the ends of the heat coil. Preferably, the sides 48 of the block 46 slope relative to the inner and outer surfaces 49 of the block. The outer surface 49 of the block and the edge of the tongue 47 conform to the shape of the cross section of the heater coil 20, that is, to the curvature of these parts. Owing to the fact that the block 46 overlaps relatively long end portions of the coil 20, and also owing to the outward inclination of the surfaces 48 of the block 46, the radii of the spinner member extending to the surfaces, collection of melted sugar is prevented at the outer side of the block 46 and between the block and the heater, and, consequently, carbonization of the sugar is prevented about the block.

In order to provide for variation in electric conditions obtainable in various fair

grounds and places of amusement, the device is provided with a combined rheostat for connecting the motor with the various sources of supply found in such places. 5 This is indicated in the diagram shown in Fig. 4. A rheostat 55 is connected to a source of supply by means of a wire 56. A movable contact 57 is connected to a second rheostat 58 and its movable arm 59 is connected to the motor 3 which is in turn connected to the source of supply through the wires 60. Thus, the rheostats 55 and 58 are connected in series with the motor. This 10 enables various quantities of current to pass through the motor and also enables the adjustment of the voltage impressed on the motor to obtain with accuracy the potential difference for which the motor is particularly designed. By operation of the arm 15 57 of the rheostat 55, relatively wide variations of resistance may be inserted in the circuit of the motor, while through the rheostat 58 may be secured, by the operation of the contact arm 59, variations in the resistance 20 within the amounts defined by the resistance coils of the rheostat 55. Thus exact 25 adjustments may be obtained for the motor over a wide range of voltage.

The heat coil 20 is connected to the contacts 15 and 22 through the rings 16 and 21 and the contacts are connected to the source of supply of current through the wires 56 and 60. A rheostat 62 may be located in the circuit of the heater 20 and the heat of 30 the heater may be adjusted by movement of the arm 63 of the rheostat, to regulate the flow of the electric current through the heater 20.

I claim:

40 1. In a candy cotton machine, a spinner member formed channel-shape and having a bottom curved in its cross section and joined with the flanges by curved portions, the bottom of the channel having slots extending from the curved portion of the top to the curved portion of the bottom of the spinner member, a heat coil formed of a flattened spirulate band arcuate in cross section and resting against the curved interior 45 surface of the spinner member, and means for electrically connecting the ends of the band with the source of supply of electric current.

2. In a candy cotton machine, a spinner 55 member formed channel-shape and having a bottom curved in its cross section and joined with the flanges by curved portions, the bottom of the channel having slots extending from the curved portion of the top to the curved portion of the bottom of the spinner member, a heat coil formed of a flattened spirulate band resting against the curved interior surface of the spinner member, a pair of rings connected to the band, a 60 65 pair of arcuate contacts for making contact

with each of the said rings, a pair of arms for supporting each pair of contacts, a pin for pivotally supporting the arms to locate the contacts on opposite sides of the ring, a tension spring for connecting the ends of the arms together for elastically pressing the contacts on opposite sides of each ring. 70

3. In a candy cotton machine, a spinner member formed channel-shape and having a bottom curved in its cross section and joined with the flanges by curved portions, the bottom of the channel having slots extending from the curved portion of the top to the curved portion of the bottom of the spinner member, a heat coil formed of a flattened spirulate band resting against the curved interior surface of the spinner member, a pair of rings connected to the band, a pair of arcuate contacts for making contact with each of the said rings, a pair of arms for supporting each pair of contacts, a pin for pivotally supporting the arms to locate the contacts on opposite sides of the ring, a tension spring for connecting the ends of the arms together for elastically 80 pressing the contacts on opposite sides of each ring, an electric motor for rotating the spinner member, and a pair of rheostats connected in series with each other and with the motor for adjusting the flow of the current 85 to the motor.

4. In a candy cotton machine, an annular spinner member, means for rotating the spinner member, the spinner member having a channel, the channel comprising a bottom 100 part and a pair of flanges extending along the said bottom part of the channel and located in planes substantially at right angles to the axis of rotation of the spinner member, the section of the said bottom part 105 in the plane of the axis of rotation of the spinner member being arcuate in form and having a length substantially equal to that of the radius of curvature of the said section, the bottom of the channel having slots for the movement of the candy cotton from the spinner member, the said flanges having curved portions between the said bottom part and the body parts of the flanges to prevent the collection of the hot sugar at the 110 corners of the said channel. 115

In witness whereof I have hereunto signed my name to this specification.

BUREN MOAD.
